UNITED STATES PATENT OFFICE.

JOSEPH S. CHIMERA, OF BUFFALO, NEW YORK.

RADIATOR-CORE.

1,164,923.

Specification of Letters Patent. Patented Dec. 21, 1915.

Application filed February 2, 1915. Serial No. 5,692.

To all whom it may concern:

Be it known that I, JOSEPH S. CHIMERA, a citizen of the United States, residing at Buffalo, in the county of Erie and State of New York, have invented certain new and useful Improvements in Radiator-Cores, of which the following is a specification, reference being had to the accompanying drawings.

10 This invention relates to certain improvements in cores for radiators, and the object of the invention is to provide a device of this general character of novel and improved construction whereby an increased water capacity is afforded.

15 The invention consists in the details of construction and in the combination and arrangement of the several parts of my improved core for radiators whereby certain important advantages are attained and the device is rendered simpler, less expensive and otherwise more convenient and advantageous for use, all as will be hereinafter more fully set forth.

20 25 The novel features of the invention will be carefully defined in the appended claim.

In order that my invention may be the better understood, I will now proceed to describe the same with reference to the accompanying drawings, wherein—

25 30 Figure 1 is a view, partly in elevation and partly in section, of a radiator core constructed in accordance with an embodiment of my invention; Fig. 2 is a sectional view taken substantially on the line 2—2 of Fig. 1; Fig. 3 is a side view, partly in elevation and partly in section, of the core as disclosed in Fig. 1; and Fig. 4 is a fragmentary view in perspective of one of the units comprising in my improved core.

35 40 My improved core, as herein embodied, comprises a plurality of units of complementary construction which when assembled afford the air passages A, the vertical water spaces S and the horizontal water spaces S', and, as herein embodied, each of the units is formed of two sheets of metal provided with the plaits 1, the plaits of one sheet being oppositely disposed relative to the other and alternate, and it is to be observed that the opposed faces of a single plait, as indicated at 2, are gradually separated from opposite sides of the sheet on converging planes whereby an increased horizontal water space S' of substantially diamond shape between the faces of the plait 1 is afforded,

45 and I arrange the intermediate portion of the sheets, as indicated at 3, in gradually converging planes extending from the front and rear edges of the sheet to a central meeting line. It is to be observed, as indicated at 6, that the vertical outer edge portion of the plait 1 is flat and disposed on inwardly converging planes so as to properly engage the intermediate portion 7 of the 50 coacting sheet to which said edge portion of the plaits are suitably secured by solder or otherwise. By this arrangement, it will be seen that each of the air spaces A is gradually restricted from its upper extremities 55 to a point substantially midway of its length. I also find it of advantage to provide the intermediate portion 7 of each of the sheets with the reinforcing rib 9 so that the unit will possess a maximum of strength. 60

65 The adjacent extremities of the sheets comprised in each of the units are provided with the interlocking flanges 4 soldered or otherwise permanently connected and the end portions 5 of the plaits are soldered. 70 The units are placed back to back with their vertical marginal portions sealed whereby the core is produced.

75 From the foregoing description, it is thought to be obvious that a core for radiators constructed in accordance with my invention is of an extremely simple and comparatively inexpensive nature and is particularly well adapted for use by reason of the convenience and facility with which it may 80 be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice. 85

90 I claim:

95 A radiator comprising a plurality of juxtaposed units, each unit consisting of a pair of opposed sheets having transversely disposed plaits extending entirely thereacross, the plaits of one sheet engaging the portion of the opposed sheet intermediate the plaits thereof, the extremities of the plaits being sealed, the opposed faces of the plaits being 100 gradually separated from opposite sides of the sheet on converging planes to afford a 105 substantially diamond shape horizontal water space, the intermediate portions of the 110

sheet being also disposed on inwardly converging planes from the opposite edges of the sheet, the intermediate portion of the inner faces of the plaits being flat and disposed on inwardly directed planes from the opposite sides of the sheet and secured to the intermediate portions of the opposed sheet of the unit, and means at the outer edges of each of the opposed sheets of the

unit for spacing the juxtaposed units and ¹⁰ forming the vertical passages of the radiator.

In testimony whereof I hereunto affix my signature in the presence of two witnesses.

JOSEPH S. CHIMERA.
